UNITED STATES PATENT OFFICE.

FREDERICK LINDLEY HUNT SIMS, OF TORONTO, ONTARIO, CANADA.

SLUDGE-FAUCET FOR CARBID-GAS GENERATORS.

936,375.

Specification of Letters Patent. Patented Oct. 12, 1909.

Application filed July 17, 1908. Serial No. 444,099.

To all whom it may concern:

Be it known that I, FREDERICK LINDLEY HUNT SIMS, of the city of Toronto, in the county of York, in the Province of Ontario, 5 Canada, have invented certain new and useful Improvements in Sludge-Faucets Particularly Adapted for Carbid-Gas Generators, of which the following is the specification.

10 My invention relates to improvements in sludge faucets particularly adapted for carbide gas generators, and the object of the invention is to devise a faucet, which will obviate any difficulty from leaking due to 15 wear and from freezing, which are incident to faucets in which the slide or gate is used on the outside of the faucet.

A further object is to insure the valve seats always being kept clean. 20 My invention consists of a flanged casting, which is suitably secured in an orifice in the tank and is provided with a threaded orifice adapted to receive the outlet pipe or 25 tubular spout of the faucet, and an inner ground projecting annular rib having a flat face, a closing gate having an operating stem connected thereto and a corresponding co-acting annular flat face and a spring plate adapted to hold the closing gate on its 30 seat when closed, the parts being arranged and constructed in detail as hereinafter more particularly explained.

Figure 1, is a sectional view of the tank of a carbide gas generator showing the location of my improved faucet. Fig. 2, is a perspective view of my sludge faucet. Fig. 3, is a horizontal section. Fig. 4, is a vertical section.

40 In the drawings like letters of reference indicate corresponding parts in each figure.

A is the main casting of my sludge faucet, which is provided with a suitable orifice A¹ to receive the inner end of the outlet pipe or tubular spout of the faucet.

45 A² is an annular rib surrounding the orifice at the inside and preferably provided with a smooth or ground face.

A³ are guiding ribs formed in the casting A at each side and provided with intermediate bosses A⁴.

50 B is a gate provided at the top with an off-set boss B¹ and on its front face with an annular rib B², which is ground so that when the gate is in its normal position the annular rib B² will lie against the rib A².

A⁵ are stops formed at the bottom of the rib A³ and designed to limit the downward movement of the gate B.

B³ are ribs formed on the rear face of the gate B. 60

C is a plate of spring metal having a central opening C¹ corresponding in size to the opening A¹ in the casting A, and held by screws D at each side as indicated, thereby exerting an inward pressure on the ribs B³ 65 of the gate B.

E is an operating rod having a threaded lower end, which fits into a correspondingly threaded hole in the boss B¹. The upper end of the rod E is connected to a lever F, which 70 is pivoted on the bracket G secured to the top of the tank. By manipulating the lever F the faucet gate may be raised and lowered.

When being raised as soon as the gate B reaches the position shown in Fig. 4, all pressure of the spring plate C is removed therefrom and it lies free and the clear water, which is finally drawn out from the tank after the sludge has been removed will serve to keep the faces of the annular ribs B² and 75 A² clear and clean. As soon as the lever F is manipulated so as to force down the gate B such gate will upon its passing the pin D be pressed upon by the plate C and more 80 and more so until it reaches the stop A⁵ 85

when the maximum pressure of the spring plate C will be exerted upon the ribs B³ and thereby the faces B² and A² brought to abut each other so closely indeed that absolutely 90 no liability of any leakage of my sludge faucet is liable.

Heretofore where the closure for the spout was at the outside, the sludge and water entering into the spout or pipe would freeze therein, and consequently the faucet became 95 useless. In my invention, however, it will be seen that as the gate B is located to the inside of the tubular spout or outlet pipe and on the outside of the machine in the water of the generator all liability of freezing is 100 avoided and operation of the faucet at all times is easy. In my invention also there is no liability of the sludge drying upon the faucets as in the old forms of faucets as they are not subject to the action of the air, but 105 are always located in the water.

What I claim as my invention is:

A sludge faucet for carbide gas generators comprising a casting having a central orifice and an annular rib surrounding the same 110

having a ground inner surface, of a gate having an annular faced rib corresponding in diameter and having a ground outer surface, ribs extending vertically on the back 5 of said gate, a flat plate of spring metal provided with a central orifice and screws located one at each end for holding the plate

against the ribs on the gate and disposed centrally of the height of the plate as and for the purpose specified.

FREDERICK LINDLEY HUNT SIMS.
